[57] CLAIM

The ornamental design for a door fastener cam, as
shown and described.

DESCRIPTION

FIG. 1 is a bottom perspective view of a fastener cam
showing my new design, with the vertical tubular ele-
ment shown broken away to indicate indeterminate
length;

FIG. 2 is a top plan view thereof;

FIG. 3 is a front elevational view thereof, the undis-
closed rear being plain and unornamented;

FIG. 4 is a bottom plan view thereof;

FIG. 5 is a fragmentary left side elevational view
thereof, with the vertical tubular element shown broken
away for clarity of illustration;

FIG. 6 is a right side elevational view of FIG. 5;

FIG. 7 is a horizontal sectional view thereof, taken
along line 7—7 of FIG. 1; and

FIG. 8 is a fragmentary vertical sectional view thereof,
taken along line 8—8 of FIG. 2.

The back of the door fastener cam is planar.
